UNITED STATES PATENT OFFICE.

CLAIRES P. ANDERSON, OF LAWSON, MISSOURI.

HEADLIGHT-TURNING MECHANISM.

Specification of Letters Patent. Patented July 14, 1914.

1,103,338.

Application filed January 27, 1914. Serial No. 814,741.

To all whom it may concern:

Be it known that I, CLAIRE P. ANDERSON, a citizen of the United States of America, residing at Lawson, in the county of Ray 5 and State of Missouri, have invented certain new and useful Improvements in Headlight-Turning Mechanism, of which the following is a specification, reference being had therein to the accompanying drawing.

10 This invention relates to lamp turning devices for automobiles and the like, and has for its object the production of a simple and efficient means for supporting the lamp in such a manner as to cause the same to be 15 easily rotated as the forward wheels of the vehicle are turned.

Another object of this invention is the production of a simple and efficient means for rotatably supporting the lamps of the 20 vehicle so as to facilitate the swinging of said lamps.

Other objects and advantages of this invention will appear throughout the following specification and claims.

25 In the accompanying drawings:—Figure 1 is a front elevation of an automobile showing the lamp turning apparatus applied thereto. Fig. 2 is an enlarged side elevation of a lamp and supporting bracket.

30 Fig. 3 is a vertical section through the supporting bearing for the lamp and bracket. Fig. 4 is a section taken on line 4—4, of Fig. 3. Fig. 5 is an enlarged sectional view showing the manner in which the lamp is 35 supported upon the supporting bracket.

Fig. 6 is a transverse section through a modified form of supporting standard for the lamp showing said standard triangular in cross section. Fig. 7 is a section taken on line 7—7, of Fig. 1. Fig. 8 is a side elevation of one of the lamp turning rods illustrating means for holding said lamp turning rod against vertical movement upon the 40 vehicle. Fig. 9 is a side elevation of the 45 lamp turning rod detached from the body of the machine.

By referring to the drawings it will be seen that 1 designates the front axle of the vehicle which supports the usual body 2.

50 The axle 1 is provided with the usual forked ends 3 to constitute axle supporting yokes, and between the yokes or forks 3 are mounted the wheel supporting axles 4, as is illustrated clearly in Fig. 1. Each of the wheel 55 supporting axles 4 is provided with a laterally projecting ear 5, which ear is provided

with an aperture 6 for receiving the reduced end 7 of the angle bar 8'. The link rod 8 is pivotally connected to the angle bar 8' and extends substantially parallel with the axle 1 for a portion of its length and is provided with an eye 9 for receiving the threaded end 10 of the lamp operating rod 11. The lamp operating rod 11 is provided with a notched portion 12, which notched portion fits within the clamp 13 carried by the front axle 1 for constituting an efficient journal for the lamp supporting rod 11 and also preventing the longitudinal movement of the lamp supporting rod 11. This rod 11 is squared throughout its length with the exception of the circular reduced or notched portion 12, which passes through the bearing 13, and the upper end of this rod 11 fits in a hollow shaft 14 carried by the bottom of the clamp 75 casing or housing 15 as will be hereinafter described. A nut 16 is threaded upon the reduced end 10 of the rod 11 to constitute efficient means for connecting the link rod 8 in firm engagement with the rod 11. The 80 hollow shaft 14 is preferably formed rectangular in cross section and is provided at its upper end with a plurality of substantially semi-circular ears 17, which ears are secured to the bottom of the lamp housing 15 by means of screws or bolts 18 of any suitable design. The hollow shaft 14 will in this manner be fixedly secured to the lamp housing 15, this construction being clearly shown in the enlarged sectional view in Fig. 90 3. It, of course, should be understood that two of the supporting rods 11 are employed as illustrated in Fig. 1, and that each rod is operated in a similar manner, it is, therefore, 95 thought necessary to only describe the construction of one of these rods, as each rod and lamp operating mechanism are duplicate in construction.

A bracket member 19 is preferably carried near each side of the machine or hood of the 100 machine, and each bracket comprises a pair of diverging legs 20, which legs are provided with laterally extending feet 21 for the purpose of constituting efficient means for connecting the bracket 19 to a support. 105 This bracket 19 comprises a substantially ring-shape body 22, thereby constituting a centrally located aperture 23 therein, through which aperture passes the hollow shaft 14 above described for facilitating 110 the connection of this shaft 14 to the lamp housing 15. The upper face of the ring 22

is provided with a ball-bearing-race 24 within which race are mounted a plurality of ball-bearings 25, which bearings also travel in the ball-bearing-race 26 formed upon the lower periphery of the annular band 27 carried by the lamp casing or housing 15. This annular band 27 is formed integral with the casing 15 and is also provided upon its outer face with an annular 5 rim or flange 28 as is illustrated clearly in Figs. 3 and 5.

For the purpose of holding the clamp housing or casing 15 against accidental displacement from the bracket 22 and at the same time allowing the free rotary movement of the lamp housing or casing 15, a sectional band 29 is employed, which band fits upon the outer face of the ring 22 and annular ring 27. This band 29 is circular 10 in shape and is formed in a pair of sections to facilitate the placing of the band around the ring 22 and annular ring 27. The band 29 is provided upon its inner face with a groove 30, which groove fits snugly around the flange or rib 28 and in this manner 15 fixedly secures the band in engagement with the lamp housing 15 to prevent the displacement of the lamp housing or casing from the ring 22. The sections of the ring 29 are 20 firmly held in engagement with the ring 22 by means of screws or other suitable means 25, thereby keying or locking the sections of the band 29 in firm engagement with the ring 22. It should be understood that the 30 lamp housing or casing 15 will at the same time have free rotary movement upon the bracket 19.

The rear section of the band 29 is provided with a laterally extending rod 32, 40 which hollow rod 32 is locked in engagement with the solid rod 33 by means of a thumb screw 34. The solid rod 33 is connected to the rear section 29 of the band of the opposite lamp so as to constitute a brace for the 45 lamps and prevent the tendency of the lamps to swing laterally relative to each other under the jar of the machine while the same is traveling. It will be seen by carefully 50 considering Fig. 9 that owing to the fact that the rods 32 and 33 are connected, that the device may be applied to different width machines.

In Fig. 6 there is shown a modified form 55 of the hollow shaft which may be used in place of the shaft 14, and this hollow shaft 14' as illustrated in Fig. 6 is formed triangular in cross section, and it should be understood that any form or shape of shaft 60 may be employed without departing from the spirit of the invention.

In view of the fact that the lamp turning rod 11 is mounted within the slot or pocket 13 of the sleeve or shaft 14, it will be seen that the lamp turning rod 11 may move vertically relative to the shaft or sleeve 14 to 65 accommodate the vertical movement of the body 2 of the vehicle upon the axle 1 thereof.

From the foregoing description it will be seen that a very simple and efficient means 70 has been produced for turning the lamps of an automobile or other vehicle simultaneously with the turning of the wheels for steering the machine or vehicle, and that owing to the particular construction of the 75 mounting of the lamp that considerable strain will be relieved from the lamp itself. The lamp is mounted upon a broad supporting base and is not supported entirely upon the turning standard, and in view of this 80 fact the lamp will have a very substantial and efficiently reinforcing supporting means.

Having thus described the invention what is claimed as new, is:—

1. A lamp turning device comprising a 85 supporting bracket provided with an integral ring portion having a race formed upon the upper face thereof, a lamp mounted upon said ring portion and provided with an annular flange upon its lower end provided 90 with a race upon the under face thereof, said annular flange provided with a projecting rib upon the side thereof, and a detachable sectional band carried by said ring and engaging said rib for allowing the rotation of 95 said lamp upon said bracket and preventing the accidental displacement of said lamp from said bracket.

2. A device of the class described comprising a supporting bracket provided with an 100 integral ring portion, a lamp mounted upon said ring portion and provided with an annular flange upon its lower end, said annular flange provided with a projecting rib portion upon the side thereof, a detachable band 105 carried by said ring and engaging said rib for allowing the rotation of said lamp upon said bracket and preventing the accidental displacement of said lamp from said bracket, and means secured to the lower end of said 110 lamp and projecting through said bracket for facilitating the rotation of said lamp upon said bracket.

In testimony whereof I hereunto affix my signature in presence of two witnesses.

CLAIRES P. ANDERSON.
